(57) **CLAIM**

The ornamental design for a spoon with edge strip, as shown and described.

DESCRIPTION

FIG. 1 is a side, top perspective view of a spoon with edge strip showing our new design;

FIG. 2 is a top view;

FIG. 3 is a bottom view;

FIG. 4 is a right side view;

FIG. 5 is a left side view;

FIG. 6 is a front view; and,

FIG. 7 is a rear view.

The broken lines shown in FIGS. 1-7 are for illustrative purposes only and form no part of the claimed design.
